(57) **CLAIM**

I claim the ornamental design for a kettle, as shown and described.

DESCRIPTION

FIG. 1 is a left front side perspective view of the kettle; FIG. 2 is a top view of the design embodiment shown in FIG. 1;

FIG. 3 is a bottom view of the design embodiment shown in FIG. 1;

FIG. 4 is a left side view of the design embodiment shown in FIG. 1

FIG. 5 is a front side view of the design embodiment shown in FIG. 1; and,

FIG. 6 is a back side view of the design embodiment shown in FIG. 1.

The broken lines in FIG. 3 are included for the purpose of illustration and form no part of the claimed design.
